SAILING FRAME STRUCTURE

Ole Goodman, 205 McGraw St., Seattle, Wash. 98109
Filed Mar. 30, 1970, Ser. No. 22,129

Term of patent 14 years

Int. Cl. D12—06

U.S. Cl. D71—1

FIG. 1

FIG. 2

FIG. 1 is a left rear perspective view of the sailing frame structure embodying my new design as viewed from the top with an air mattress shown in dotted lines for illustrative purposes;

FIG. 2 is a right front perspective view as viewed from the bottom with an air mattress shown in dotted lines for illustrative purposes.

I claim:

The ornamental design for a sailing frame structure, substantially as shown and described.
